UNITED STATES PATENT OFFICE.

HOWARD M. DUDLEY, OF PHILADELPHIA, PENNSYLVANIA.

FABRIC-DYEING MACHINE.

1,274,525.

Specification of Letters Patent. Patented Aug. 6, 1918.

Application filed July 25, 1917. Serial No. 182,611.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Fabric-Dyeing Machines, of which the following is a specification.

My invention relates to dyeing machines and refers particularly to a device suitable for the dyeing of piece goods.

One object of my invention is a device whereby at the same time several pieces of woven fabric may be dyed evenly and equally.

Another object of my invention is a device whereby the conditions incident to the dyeing of several pieces of woven fabric at the same time, may be uniform.

Another object of my invention is a device whereby the several pieces to be dyed may be severally wound upon the device prior to dyeing, and may be unwound therefrom after dyeing.

Another object of my invention is a device whereby several pieces of woven fabric may be simultaneously treated to a uniform amount of dye liquor forced therethrough, while revolving within a dye liquor.

Another object of my invention is a device whereby the width of the foraminous plate around which a fabric is wound and through which a dye liquor is forced, can be changed to agree with the width of a fabric wound thereon.

Another object of my invention is a device whereby the dyed condition of each of several lengths of cloth may be accurately measured without disturbing the cloth being dyed.

These and other objects of my invention will be evident upon a consideration of my specification, drawings and claims.

The dyeing of piece goods presents many difficulties, especially in those processes in which the dye liquor is forced through the rolled goods. In this method of dyeing considerable difficulty is met in endeavoring to produce even results, as all portions of the goods must receive absolutely equal treatments, as regards penetration, amount and strength of dye liquor and time of operation.

Another difficulty in the dyeing of goods of this character is that it is almost impossible to maintain exactly the same conditions in successive dyeings, and unless this is accomplished the several pieces of goods will not be of the same shade or strength and hence will not be matchers for each other.

Another difficulty is the time and labor necessary in the rolling, handling and dyeing of the several pieces of goods.

Another difficulty is that in order to test the dyed condition of the fabric, it is necessary, in the present employed methods, to tear off a piece of the dyed fabric, thus causing a considerable waste of goods and a disturbance of the rolled fabric.

The device of my invention overcomes all of the above, and many other difficulties incident to the dyeing of piece goods and presents a method whereby this may be accomplished readily, economically and perfectly.

My device comprises in a broad way a device in which several rolls of woven fabric may be formed, and dyed and washed simultaneously and equally with a maximum of speed and a minimum expenditure of time, labor and dyes.

One form of the dyeing machine of my invention is shown in the accompanying drawings in which similar parts are designated by similar numerals.

Figure 1 is a vertical cross-section of one form of a device of my invention.

Fig. 2 is a cross-section through the line 2-2 of Fig. 1.

Fig. 3 is an end view of Fig. 1, with the top open, in the direction of the arrow 3.

Fig. 4 is an enlarged view of the clutch mechanism.

Fig. 5 is a broken side view, partly in cross-section, of one of the revolute foraminous cylinders, with an employed method of revolving the same.

Fig. 6 is a fragmentary section through the line 6-6 of Fig. 2.

Fig. 7 is a broken view showing a testing device and method of attaching the same.

Fig. 8 is a cross-section through the line 8-8 of Fig. 1.

Fig. 9 is a broken cross-section of one of the foraminous cylinders,

Fig. 10 is a broken end view of Fig. 9.

Fig. 11 is a broken cross-section of a modification of one of the foraminous cylinders.

5 Fig. 12 is a broken end-view of Fig. 11.

The device as illustrated comprises a dyeing chamber formed by the bottom member 20 and the top member 21, the latter being pivotally attached to the former at 22, the 10 top and bottom being capable of attachment to each other by means of the thumb-screws 23, 23. The ends of the dyeing chamber are formed by the annular members 24, 24^A which extend outwardly into the conical 15 shaped members 25, 25^A, the latter extending outwardly into the cylindrical members 26, 26^A, which are revoluble around the pipes 27, 27^A, the latter being connected to a means for forcing a liquid therethrough. 20 The top 21 has a pipe 28 leading to the source of liquid to allow a continuous circulation through the device, and the bottom 20 has a pipe 29 with the valve 30 to allow the 25 contents of the dyeing chamber to be withdrawn. Fixedly attached to the member 24^A is a cogged wheel 31, meshing with the worm gear 32 carried by the shaft 33 connected to a source of power and upon which it revolves freely. A loose sprocket wheel 30 34 is also carried by the shaft 33. A double faced clutch 35 is fixedly attached to the shaft 33 and revoluble therewith, and is capable of enmeshment with either the worm gear 32 or the sprocket wheel 34, to cause 35 the revolution of either as desired, by means of the shift handle 36, pivoted at 37 and capable of being fixed in the desired position by means of the locking bolt 38 movable within the opening 39 of the arm 40. The 40 sprocket wheel 34 is connected by means of the chain belt 40 with the sprocket wheel 41, fixedly attached to the shaft 42, revoluble within the bearing 43, the chain 40 riding over the guide rollers 44, 45. The other 45 extremity of the shaft 42 carries a fixedly attached pulley 46, connected by means of the belt 47 to the pulley 48 fixedly attached to the shaft 49. The shaft carries the fixedly attached bevel gear 50. The support 51 has 50 an extended member 52 within which is the arc-shaped opening 53. The shaft 49 is revoluble in the bearings 54 and 55. A shaft 56, revoluble within the bearings 57 and 58, has a bevel gear 59 at one end, 55 meshed with the bevel gear 50, and a cogged wheel 60 at the other end capable of being meshed with the cogged member 61. The member 62 carrying the bearings 57 and 58, is revoluble around the sleeve surrounding the shaft 49, and has a fixedly attached threaded bolt 63 extending through the opening 53. On the other side of the member 52 is a threaded wheel 64, capable of being threaded upon the bolt 63 and so arranged that it will fixedly position the bolt 60 65

63 in any desired position in the opening 53. By moving the bolt 63 along and within the opening 53, the shaft 56 may be moved from its upright position shown in Figs. 1 and 3; in which position the cogged wheel 70 60 is not meshed with the cogged member 61, into the position shown in Fig. 5, in which the cogged wheel 60 and the cogged member 61 are meshed, the shaft 56 being maintained in either position as desired by 75 means of the threaded wheel 64.

Spaced within the conical members 25, 25^A are the imperforate conical members 70, 70^A. A series of plates 71, 71, 71^A, 71^A extend across the space between the members 25, 70 80 and 25^A, 70^A.

A foraminous cylinder 72 has a series of parallel openings or slots 73, 73. The cylinder 72 is attached to the annular members 75, 75^A by means of the splines 74, 74^A, 85 which allows the members 75, 75^A to slide along the surface of the cylinder 72, but causes them to revolve in unison therewith. The members 61, 61^A abut upon the surfaces 150, 150^A of the members 75, 75^A and are 90 slidable over the outer face of the foraminous cylinder 130.

A series of right and left turn buckles 76, 76, 76^A, 76^A connect the members 75, 61 and 75^A, 61^A and cause the separation of these 95 two sets of members at any predetermined position from each other. The reels composed of the foraminous cylinder 72, the members 61, 61^A and the members 75, 75^A are thus integral with each other and are 100 capable of a revolving motion within a bearing or bushing within the members 24, 70 and 24^A, 70^A.

Central of the dyeing chamber and extending between the inner portions of the 105 members 70, 70^A is the fixed shaft 77 carrying a cogged wheel 78, slidable upon the shaft 77 but held from revolution by the spline 79. A lever 80, pivotally attached at 90 to the member 91 of the cogged wheel 78 and at 92 to the support 93, is capable by 110 its movement of meshing the cogged wheel 78 with all of the cogged members 61, 61, thus locking them in a fixed position relative to each other. The thumb-set screw 94, 115 movable within the slot 95, acts as a locking medium for the motion of the lever 80.

Each one of the reels carries a testing device, the construction of which is shown in Fig. 7. This testing device comprises a reel 120 formed by the end flanges 100, 100 and the foraminous cylinder 101. Each interior end of the reel is connected to pipes 102, 102 having the valves 103, 103, said pipes being threaded into the openings 104, 104 of the 125 member 61^A which connect with the space 105. Openings 106, 106 connect the space 105 with the source of liquor as shown.

A series of walls 110, 110, 110^A, 110^A extending from the inner face of the forami- 130

nous cylinders 72, 72 to the spaces between the members 70, 70^A and 25, 25^A divide the spaces within the cylinders 72, 72 into a series of conduits 111, 111, 111^A, 111^A 5 through which the dye liquor passes.

A foraminous cylinder 130 spaced from the cylinder 72 is integral with the member 75, 75^A and abuts upon the upper faces of the members 75, 75^A at 131, 131^A, the members 61, 61^A being slidably movable over the outer face of the cylinder 130 and capable of covering and closing some of the openings therein.

The foraminous cylinder 130 is composed 15 of a series of parallel downwardly disposed triangular members 132, 132, connected at their upper edges to form an edge 133 upon which the cloth 140 rests, spaces 134, 134 allowing of the liquid to be dispersed in its 20 upward movement.

In the modified form of the foraminous cylinder 130 shown in Figs. 11 and 12 the upper edge 133 is serrated into the upwardly extended pointed members 135, 135 25 with the spaces 136, 136 between.

Any suitable means for heating a liquor in the dyeing chamber may be employed, and any suitable foraminous covering for the cloth 140 may be employed.

30 The operation of the device is as follows: The top 21 is opened into the position shown in Fig. 3. The shaft 56 is revolved until the cogged wheel 60 is in mesh with one of the cogged members 61 (Fig. 5). The lever 36

35 (Fig. 4) is moved to mesh the clutch 35 with the wheel 34 and power imparted to the shaft 33. The toothed wheel 34 (Fig. 3) revolves the toothed wheel 41 by means of the chain 40, which in turn revolves the shaft

40 42, the latter revolving the shaft 49 by means of the pulley 46, the belt 47 and the pulley 48. The revolution of the shaft 49 (Fig. 5) causes the revolution of the bevel wheels 50 and 59, the shaft 56, the cogged

45 wheel 60 and the cogged member 61, thus causing a revolution of this particular reel. The cloth 140 is then wound around the foraminous cylinder 130 by means of this revolution of the reel. When the cloth 140

50 is wound upon the cylinder 130, the two members 61, 61^A are brought into intimate contact with the edges of the rolls by turning the buckles 76, 76^A, thus sliding the members 61, 61^A over the surface of the cylinder

55 130 and closing all of the openings therein except those covered by the cloth. The reel of the testing device is then removed, cloth 141 wound around the foraminous plate and the testing device replaced. The cogged

60 wheel 60 is then revolved into the position shown in Fig. 1, thus disengaging it from cogged member 61. The lever 36 (Fig. 4) is then moved to connect the clutch 36 with the worm gear 32, thus revolving the 65 device until the next reel is in position for

engagement between the cogged wheel 60 and the cogged member 61, and cloth wound thereon. These operations are repeated until cloth is wound upon all of the reels and testing devices. The cogged wheel 60 is then 70 placed in the position shown in Fig. 3, the top 21 is placed upon the bottom 20 and clamped by means of the clamping members 23. The device is then revolved by means of the worm-gear 32, and dye liquid introduced through the pipes 27, 27^A, and it is thus distributed equally and evenly through the spaces between 70, 25 and 70^A, 25^A, the conduits 111, 111^A, the foraminous cylinder 75 80 80 the space around it, the foraminous cylinder 130 and the goods 140 into the dyeing chamber, from whence it flows through the pipe 28 back to the source of liquid supply for continuous circulation. During this dyeing operation, the cloth 141 in the various testing devices is receiving similar treatment and, as desired, the valves 103, 103 may be closed, the testing device removed and the cloth examined to determine 85 its condition.

Under the above conditions, the various reels are free to revolve upon their own axes, but if it is desired to prevent this, the lever 80 is moved to engage the cogged wheel 78 with the cogged members 61, 61. 90

When the dyeing is finished, the supply of dye liquor is interrupted and the contents of the dyeing chamber are removed through the pipe 29 by opening the valve 30. The valve 30 is then closed and clear water, 100 for washing purposes, forced through the device in a manner similar to that employed for dyeing.

The goods may then be removed by reversing the process used in winding them 105 upon the reels.

I do not limit myself to the particular number, form, or arrangement of parts as shown and described, all of which may be varied without going beyond the scope of 110 my invention as described and claimed.

What I claim is:

1. A dyeing machine, comprising a dyeing chamber, a series of hollow reels within the dyeing chamber and revoluble therein, each reel composed of a foraminous member and outwardly extended imperforate flanges, the foraminous member being capable of having a fabric wound thereon, means for forcing a liquid equally into all of the hollow reels and from thence through the foraminous members and the fabrics wound thereon, means for submerging the reels continuously within a liquid within the dyeing chamber, and means for revolving the series 115 120 125 of reels.

2. A dyeing machine, comprising a dyeing chamber, a series of hollow reels within the dyeing chamber and revoluble therein, each reel composed of a foraminous member 130

and outwardly extended imperforate flanges, the foraminous member being capable of having a fabric wound thereon, means for winding a fabric upon each reel, means for 5 forcing a liquid from the interior of the hollow reels outwardly into the dyeing chamber during the revolution of the series of reels, means for revolving the series of reels and means for causing a constant circulation of the liquid through the device.

3. A dyeing machine, comprising a dyeing chamber, a series of hollow reels within the dyeing chamber and revoluble therein, each reel composed of a foraminous member and 15 outwardly extended imperforate flanges, the foraminous member being capable of having a fabric wound thereon, means whereby a portion of the foraminous members may be made impervious to a liquid, 20 means for winding a fabric upon each reel, means for forcing a liquid into the interior of reels and from thence outwardly through the foraminous member into the dyeing chamber, and means for revolving the series 25 of reels.

4. A dyeing machine, comprising a dyeing chamber, a series of hollow reels within the dyeing chamber and revoluble therein, each reel composed of a foraminous member and 30 outwardly extended imperforate flanges, the foraminous member being capable of having a fabric wound thereon, a series of tubular members within each reel leading from the ends thereof to the inner surface of the 35 foraminous member, means for revolving the series of reels, means for forcing a liquid through the tubular members and the foraminous members into the dyeing chamber during the revolution of the reels, and means 40 whereby the liquid may be withdrawn from the upper portion of the dyeing chamber for its constant circulation through the device.

5. A dyeing machine, comprising a dyeing 45 chamber, a series of hollow reels within the dyeing chamber and revoluble therein, each reel composed of a foraminous member and outwardly extended imperforate flanges, the foraminous member being capable of having 50 a fabric wound thereon, divergent openings in the foraminous members, means for forcing a liquid equally into all of the hollow reels and from thence through the foraminous members and the fabrics wound thereon, means for submerging the reels continuously within a liquid within the dyeing 55 chamber, and means for revolving the series of reels.

6. A dyeing machine, comprising a dyeing 60 chamber, a series of hollow reels within the dyeing chamber and revoluble therein, each reel composed of a foraminous member and outwardly extended imperforate flanges, the foraminous member being capable of having 65 a fabric wound thereon, divergent openings

in the foraminous members, means for closing the openings in a portion of the foraminous members, means for revolving the series of reels around a common axis of revolution, means for winding a fabric upon 70 each reel, and means for forcing a liquid from the interiors of all the reels outwardly into the dyeing chamber.

7. A dyeing machine, comprising a dyeing chamber, a series of hollow reels within the dyeing chamber and revoluble therein, each reel composed of a foraminous member and outwardly extended imperforate flanges, the foraminous member being capable of having 75 a fabric wound thereon, a series of tubular members within each reel leading from the ends thereof to the inner surface of the foraminous member, divergent openings in the foraminous members, means for revolving the series of reels, means for forcing a 80 liquid through the tubular members and the foraminous members into the dyeing chamber during the revolution of the reels, and means whereby the liquid may be withdrawn from the upper portion of the dyeing 85 chamber for its constant circulation through the device.

8. A dyeing machine, comprising a dyeing chamber, a series of hollow reels within the dyeing chamber and revoluble therein, each reel composed of a foraminous member and outwardly extended imperforate flanges, the foraminous member being capable of having 90 a fabric wound thereon, means for submerging the reels continuously within a liquid within the dyeing chamber, means for revolving each reel independently of the other reels, means for revolving the series of reels around a common axis of revolution, and means for forcing a liquid into the hollow 95 reels and from thence through the plates into the dyeing chamber.

9. A dyeing machine, comprising a dyeing chamber, a series of hollow reels within the dyeing chamber and revoluble therein, 110 each reel composed of a foraminous member and outwardly extended imperforate flanges, the foraminous member being capable of having a fabric wound thereon, a series of tubular members within each reel leading 115 from the ends thereof to the inner surface of the foraminous member, means for revolving each reel independently of the other reels, means for revolving the series of reels, means for forcing a liquid through the tubular members and the foraminous members into the dyeing chamber during the revolution of the reels, and means whereby the 120 liquid may be withdrawn from the upper portion of the dyeing chamber for its constant circulation through the device.

10. A dyeing machine, comprising a dyeing chamber, a series of hollow reels within the dyeing chamber and revoluble therein, each reel composed of a foraminous member 125

- and outwardly extended imperforate flanges, the foraminous member being capable of having a fabric wound thereon, divergent openings in the foraminous members, means 5 for closing the openings in a portion of the foraminous members, means for revolving each reel independently of the other reels to allow the winding of a fabric thereon, means for revolving the series of reels 10 around a common axis of revolution, and means for forcing a liquid from the interiors of all the reels outwardly into the dyeing chamber.
11. A dyeing machine, comprising a dyeing chamber, a removable top to the dyeing chamber, a series of hollow reels within the dyeing chamber and revoluble therein around a common axis of revolution, each reel being composed of a hollow foraminous 15 cylinder, with outwardly extended imperforate flanges, means within the reel whereby a liquid may be impinged equally over the inner face of the foraminous cylinder, means for revolving the series of reels around a common axis, means exterior to the dyeing chamber for revolving each reel independently, means for locking the reels from independent rotation, means for forcing a liquid through the hollow reels and the foraminous 20 cylinders into the dyeing chamber, and means for producing continuous circulation of the liquid through the device.
12. A dyeing machine, comprising a dyeing chamber, a removable top to the dyeing chamber, a series of hollow reels within the dyeing chamber and revoluble therein around a common axis of revolution, each reel being composed of a hollow foraminous cylinder with outwardly extended imperforate flanges, a series of conduits within the hollow reels connecting the ends of the reels with the inner faces of the foraminous cylinders, means for revolving the series of 25 reels, means for revolving each reel independently of the others, means for locking the reels from independent rotation, means for forcing a liquid inwardly into the reels from both ends thereof, and means for the continuous circulation of the liquid through 30 the device.
13. A dyeing machine, comprising a dyeing chamber, a removable top to the dyeing chamber, a series of hollow reels within the dyeing chamber and revoluble therein around a common axis of revolution, each reel being composed of a hollow foraminous cylinder, with outwardly extended imperforate flanges, the foraminous cylinders having divergent openings, means within the 35 reel whereby a liquid may be impinged equally over the inner face of the foraminous cylinder, means for revolving the series of reels around a common axis, means exterior to the dyeing chamber for revolving each reel independently, means for locking 40 the reels from independent rotation, means for forcing a liquid inwardly into the reels from both ends thereof, and means for the continuous circulation of the liquid through the device.
14. A dyeing machine, comprising a dyeing chamber, a series of hollow reels within the dyeing chamber and revoluble therein, each reel composed of a foraminous member and outwardly extended imperforate flanges, the foraminous member being capable of having a fabric wound thereon, a smaller testing device connected with the interior of a reel and revoluble therewith, means for forcing a liquid equally into all of the hollow reels and from thence through the foraminous members and the testing device and means for revolving the series of 45 reels.
15. A dyeing machine, comprising a dyeing chamber, a series of hollow reels within the dyeing chamber and revoluble therein, each reel composed of a foraminous member and outwardly extended imperforate flanges, the foraminous member being capable of having a fabric wound thereon, a series of tubular members within each reel leading from the ends thereof to the inner surface of the foraminous member, a smaller testing device 50 connected with the interior of a reel and revoluble therewith, means for revolving the series of reels, means for forcing a liquid through the tubular members, the foraminous members and the testing device into the dyeing chamber during the revolution of the 55 reels and means for the continuous circulation of the liquid through the device.
16. A dyeing machine, comprising a dyeing chamber, a series of hollow reels within the dyeing chamber and revoluble therein, each reel composed of a foraminous member and outwardly extended imperforate flanges, the foraminous member being capable of having a fabric wound thereon, divergent 60 openings in the foraminous members, means for closing the openings in a portion of the foraminous members, a smaller testing device connected with the interior of a reel and revoluble therewith, means for revolving the series of reels around a common axis of revolution, means for winding a fabric upon each reel, and means for forcing a liquid from the interiors of all the reels outwardly 65 into the dyeing chamber.
17. A dyeing machine, comprising a dyeing chamber, a removable top to the dyeing chamber, a series of hollow reels within the dyeing chamber and revoluble therein around a common axis of revolution, each reel being composed of a hollow foraminous cylinder with outwardly extended imperforate flanges, a series of conduits within the hollow reels connecting the ends of the reels with the inner faces of the foraminous cylinders.

ders, means for revolving the series of reels, means for revolving each reel independently of the others, means for locking the reels from independent rotation, a smaller testing device connected with the interior of a reel and revoluble therewith, means for forcing a liquid inwardly into the reels from both

ends thereof, and means for the continuous circulation of the liquid through the device.

Signed at New York in the county of 10
New York and State of New York this 23rd
day of July, 1917.

HOWARD M. DUDLEY.
